UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR LAYING THE SOLES OF BOOTS AND SHOES.

Application filed August 3, 1917. Serial No. 184,347.

To all whom it may concern:

Be it known that I, LOUIS A. CASGRAIN, a citizen of the United States, residing at Beverly, in the county of Essex and State of Massachusetts, have invented certain Improvements in Machines for Laying the Soles of Boots and Shoes, of which the following description, in connection with the accompanying drawings, is a specification, like reference characters on the drawings indicating like parts in the several figures.

This invention relates to machines for use in the manufacture of boots and shoes and more particularly to machines for use in laying the soles of boots and shoes. The general object of the invention is to provide an improved sole laying machine by the use of which soles may uniformly be laid properly and quickly, which will produce work superior to that obtainable heretofore, and which will materially reduce the cost of sole laying operations.

The invention is illustrated as embodied in a machine especially designed for laying rubber soles on shoes of the type in the manufacture of which the rubber soles are laid while in an unvulcanized or "green" condition and are subsequently permanently attached by vulcanization, each of the soles being usually cut initially to final size and provided with a beveled edge for the purpose of enabling the margin of the sole to be forced into adhesion to the sides of the upper adjacent to the shoe bottom.

Heretofore, so far as is known, such soles have been uniformly laid by hand, the customary method of laying an unvulcanized rubber sole consisting in positioning a sole upon a lasted shoe bottom and then connecting the sole to the contour of the shoe bottom and forcing its marginal portion into adhesion to the sides of the shoe adjacent to its bottom by the use of a relatively heavy hand roller which the operator worked back and forth over the sole until the entire surface was roller.

This method of laying rubber soles is not only exceedingly laborious and slow but, even with the exercise of the greatest possible skill on the part of the workman, it is extremely difficult, if not impossible, for example, to treat all portions of the sole with sufficient uniformity to prevent the forma-

tion of air pockets which later cause defective vulcanization of the shoe. In practice it 55 has been the common experience that a relatively large number of shoes defective in this and other ways have been produced which necessarily had to be disposed of at a serious loss to the manufacturers.

A particular object of the present invention is to provide a sole laying machine especially adapted for laying unvulcanized rubber soles, by the use of which such soles may be laid with precision and uniformity and 65 which shall have the greatest possible output capacity consistent with satisfactory work. It is to be understood, however, that, while the invention is herein described with relation particularly to its applicability to 70 use in laying unvulcanized rubber soles, the invention is not intended to be limited thereby since it is appreciated that the invention as a whole or various features thereof may have other and different uses.

With these and other objects in view and in accordance with important features of the invention, the illustrated machine comprises a novel organization of means for holding a shoe against pressure applied to the bottom 80 of the shoe and means for applying sole laying pressure to the shoe constructed and arranged to be rendered effective to apply pressure to the bottom of the shoe and to the sides of the shoe adjacent to the shoe bottom 85 or to the edges of the shoe sole upon relative movement of the pressure applying means and the shoe holding means. In the illustrated embodiment of the invention, the pressure applying movement is effected by 90 bodily movement of translation of a carrier for the pressure applying means relatively to the shoe supporting means.

The machine herein shown is especially designed to force the marginal portion of a 95 shoe sole into adhesion to the sides of the shoe adjacent to the shoe bottom while the shoe bottom is under sole laying pressure. A further important feature of the invention consists in a construction and arrangement of the pressure applying means such that the pressure applied to the sides of the shoe adjacent to the shoe bottom is directed substantially perpendicularly to the sides of the shoe without any substantial component 100 of force in the direction of the height of the

shoe, thus avoiding frictional drag upon the sides of the shoe. Practical experience has demonstrated that by the application of pressure in this manner, either to the sides of a 5 shoe or to the upstanding marginal edges of the shoe sole, an unvulcanized or green rubber sole can be readily and expeditiously conformed to the shoe without producing any objectionable distortion of the sole such 10 as would impair the wearing qualities of the shoe and also be detrimental to the appearance of the shoe. Moreover, such application of sole laying pressure, without impairing the usefulness of the organization for treatment of shoes of other types, is particularly 15 well adapted for forcing the sole margin and the "foxing" which extends along the sides of rubber soled shoes of certain types into proper adhesion, thus rendering separate 20 hand treatment of the foxing unnecessary, and at the same time properly overlapping the marginal edge of the rubber sole on the sides of the upper adjacent to the shoe bottom. 25 Other noteworthy features of the invention reside in the construction and arrangement of the pressure applying means. As shown, the pressure applying means comprises a resilient and self-conforming mold 30 provided with a shoe bottom pressing surface approximately complementary to the shape of a shoe sole and provided with resilient side walls adapted to be converged into pressure applying relation to the shoe. 35 In accordance with another feature of the invention, the illustrated machine is organized to receive and position initially a shoe sole and to permit a lasted shoe to be placed in the mold with its bottom face laid upon 40 the sole and properly positioned relatively to the sole and to the pressure applying means without any preliminary location of the sole on the shoe bottom or temporary attachment thereto, thus necessitating a prior 45 manual operation. At the same time, the pressure applying means may be used, if desired, to operate upon a shoe on which the sole has previously been positioned and to which it has been preliminarily attached. 50 To enable the operator to see what he is doing when assembling the sole and shoe, the jack employed for holding the shoe is automatically held in a laterally displaced position during such assembly but is shifted to 55 holding position above the pad before the machine operates to effect the laying pressure, which operation of the machine occurs while the sole and shoe remain in the positions of first assembly on the pad. 60 Further features of the invention consist 65 in the provision of a body of fluid interposed between a fluid container and the pressure applying means. As shown, the construction is such that the body of fluid is of constant volume, relative movement of the pres-

sure applying means and the shoe holding means causing the flexible pressure applying means to apply pressure to the bottom of the shoe by pressure exerted through the fluid and to apply pressure to the sides of the shoe 70 adjacent to the bottom through bodily movement or displacement of the fluid.

Still other features of the invention consist in novel auxiliary pressure applying means provided especially to facilitate the 75 operation of the machine upon shoes of relatively small sizes.

Other objects and features of the invention will be apparent from the following description when considered in connection 80 with the accompanying drawings and the invention will be set forth in the appended claims.

Fig. 1 of the drawings is an end elevation of a machine embodying one form of the 85 present invention.

Fig. 2 is a cross-section of the pressure applying means, illustrating its operation upon a shoe.

Fig. 3 is a front elevation showing the 90 twin sole laying mechanisms with which the machine is provided, one mechanism being shown partly in section.

Fig. 4 is a plan view of a portion of one 95 of the pressure applying means illustrating the work positioning means.

Fig. 5 is a perspective sectional view of one of the pressure applying pads.

The illustrated machine is provided with 100 twin mechanisms one of which is adapted to lay an unvulcanized rubber sole upon a right shoe and the other mechanism to lay a sole upon a left shoe. Both sole laying mechanisms being substantially identical, only one mechanism will be described in detail, the same reference characters being used 105 to designate similar parts of both mechanisms.

As shown, each sole laying mechanism comprises an upright frame 2 having an overhanging head portion on which is mounted a shoe support or jack for holding a shoe against pressure applied to the bottom of the shoe. This jack comprises a hollow arm 4 pivotally mounted at its upper end upon a 110 shaft 6 in the head of the frame 2 and receiving a rod 8 the projecting lower end of which carries a cross arm 10 extending longitudinally of the machine and having a toe post 12 and a heel post 14 adjustably secured to its respective ends by nuts 15. The rod 8 is adjustably held in the arm 4 by a nut 16 which is threaded into the lower end of the said arm and engages a collar 18 on the rod 8. A compression spring 20, also received in the hollow arm 4 and engaging the collar 18 on the rod 8, serves to provide a yielding support for the shoe against the sole laying pressure and to compensate for any variations in the height of the last. A 130

spring 22 secured at one end to the arm 4 and at its other end to the frame 2 maintains the shoe support or jack normally in an inoperative position away from the operator, as 5 indicated in full lines in Fig. 1.

The jack is moved into the operative position indicated by dotted lines, Fig. 1, to hold the shoe against sole laying pressure, by means of a treadle 24 which is fulcrumed on 10 a shaft 26 in the frame and has its rear end connected at 27 by a rod 28 to one end of a lever 30 fulcrumed on a shaft 32 in the head of the frame. The forward end of the lever 30 is arranged to engage a cam 15 surface 34 provided on the back of the arm 4 directly below the shaft 6 to cause the arm 4 to be swung forward into a substantially vertical position. A bolt 36 threaded through a lug 38 formed on the arm 4 serves 20 as an adjustment to determine the position of the jack to hold the shoe during the application of sole laying pressure. In laying unvulcanized rubber soles upon the lasted bottom of a shoe, it is extremely im- 25 portant that a uniform sole laying pressure be applied to the shoe to conform the sole to the contour of the shoe bottom and to prevent air pockets from being formed between the shoe bottom and the sole which would 30 later cause defective vulcanization of the shoe. Also it is essential in providing a satisfactory machine for laying unvulcanized soles to cause the sole laying pressure to be directed substantially perpendic- 35 ularly to the tread surface of the sole, that is, substantially perpendicular to the bottom of the sole and to the adjacent side faces of the shoe, since such soles, ordinarily extend over on to the side faces of the shoe adjacent 40 to the bottom and, being more or less plastic, are easily distorted, thus detracting from the neat appearance of the shoe and preventing proper attachment of the sole to the shoe.

45 In the illustrated embodiment of the invention, the means for applying sole laying pressure for laying the sole on the shoe, which means are hereinafter referred to as the pressure applying pad, is so formed 50 and arranged as to apply a substantially perpendicular sole laying pressure to the bottom of the shoe and to the sides of the shoe adjacent to the shoe bottom when bodily movement of translation of a carrier 55 for the pressure applying pad relatively to the jack is effected. As herein shown, the pressure applying pad comprises a metal fluid container or chamber 40 of a suitable shape to receive a shoe and having an out- 60 wardly projecting flange 42 formed along its upper edge. This chamber is sealed by a sole receiving pad or mold 44 which is disposed across the top of the container and has its marginal edges clamped between 65 the flange 42 of the container and a suitably

shaped rim 46 which is secured to the flange 42 by screws 48 so located as not to pass through the margin of the pad or mold 44. A bead formed on the under surface of the rim 46 and co-operating with a similar bead 70 on the flange 42 serves further to secure the mold 44 to the container 40. The sole engaging pad or diaphragm 44 herein shown consists of a resilient elastic material such as rubber and it is formed and arranged to constitute a conformable shoe and shoe sole receiving mold or matrix of a normal shape to present a shoe bottom pressing surface 50 approximental to the contour of the bottom of a shoe and having side walls 52 adapted to 80 be converged into pressure applying relation to the side faces of the shoe adjacent to the shoe bottom.

For the purpose of causing the mold 44 to be forced into exact conformation with 85 the bottom and the adjacent side faces of the shoe and to cause a uniform sole laying pressure to be exerted upon the shoe when the pressure applying pad is moved bodily relatively to a shoe held by the jack, the 90 container 40 is provided with a constant volume of a mobile or displaceable medium adapted to act upon the bottom 50 and side walls 52 of the pad. In the illustrated machine, this medium comprises a body of 95 fluid, preferably of water, of a sufficient constant volume to cause a uniform translation of the pressure to be exerted upon the shoe engaging walls of the mold 44 to force the mold into uniform sole laying pressure upon 10 the shoe. This application of pressure by the mobile body of fluid is such as to cause the walls of the mold to exert a substantially perpendicular sole laying pressure upon all 10 portions of the bottom and the side faces 10 of the shoe substantially simultaneously, this application of sole laying pressure preventing distortion of the sole and also enabling the marginal portion of the sole to be 11 rolled over on to the sides of the shoe with greater accuracy than is possible by the hand roll heretofore used. To insure a substantially perpendicular pressure being applied to the sides of the shoe adjacent to the bottom by the side walls 52 of the mold 40 11 so as not to distort the margin of the shoe sole as it is forced over on to the sides of the shoe and, also, so as not to disturb the fox- 12 ing which usually extends along the marginal side faces of the shoe the side walls 52 are sloped outwardly from the shoe bottom pressing surface 50 of the mold. These walls 52 are preferably so sloped with respect to the shoe bottom pressing surface 50 as to enable them to be converged into pressure applying 12 relation to the shoe after a substantial part of the sole laying pressure has been applied to the bottom of the shoe. By reason of this arrangement the walls 52 of the mold direct a substantially perpendicular pres- 13

sure upon the sides of the shoe without any substantial component of force in the direction of the height of the shoe thus eliminating any frictional drag of the 5 walls upon the sides of the shoe during the relative pressure applying movement between the pressure applying pad and the jack. Moreover, the side walls exert the necessary pressure upon the foxing which 10 ordinarily extends along the marginal sides of the shoe to force it into proper adhesion to the upper and thus render a separate hand treatment of the foxing unnecessary.

In the illustrated machine, the pressure 15 applying movement of the pad is effected by a power operated pad carrier 56, the upper end of which is formed to provide a table 58 upon which the pad is detachably mounted by means of tap screws 60. This carrier is 20 guided for vertical reciprocation by two pairs of links 62, 64, each pair being disposed on either side of the carrier 56 and pivoted at their forward ends upon studs 66, 68, respectively of the carrier and at their 25 rear ends on a stud 70 and a shaft 72 respectively on the frame 2. The bodily vertical movement of translation of the carrier 56 to establish a pressure applying relation between the pad and the shoe is effected by an 30 eccentric cam 74 which engages a cam roll 78 provided on the lower end of the carrier. The cam 74 is loosely mounted on shaft 80 and is connected thereto for a predetermined length of time by means of a treadle-controlled 35 one revolution clutch connection to the shaft 80 of the machine. The shaft 80 is continuously driven by a fast pulley 84 on the main or driving shaft 72 which transmits power through the sprocket 86 and a 40 chain belt 88 to a much larger sprocket 90 fast on the shaft 80. Therefore the speed of rotation of the shaft 80 is determined by that of the shaft 72 so that each complete rotation of the shaft 80 is effected during a 45 period of time controlled by that of the driving mechanism. The illustrated one revolution clutch connection between the eccentric cam 74 and the cam shaft 80 includes a disk clutch member 92 which is fast on the shaft 50 80 and located beside the cam 74, the disk being provided with two longitudinally extending slots 94. Pivottally mounted on one 55 side of the eccentric cam 74 and at substantially the highest point in the cam throw is a spring actuated dog 96 which is adapted to engage either of the slots 94 in the disk 92, to cause rotation of the eccentric with the disk. The dog 96 had a laterally projecting lug 97 (Fig. 3) and is normally held out of 60 engagement with the slots 94 by an arm 98 fulcrumed on the shaft 26 and having its upper end provided with an inclined rib 100 indicated by dotted lines in Fig. 1, which rib is adapted to engage the lug 97 of the dog 96 to maintain it inoperative. This arm 98

is moved out of engagement with the dog 96 to enable the dog to locate itself in one of the slots 94 by a pawl 102 which is pivoted at 104 to the upper end of an arm 106 of the treadle lever 24 and has its forward 70 end engaging abutments 108 formed on the arm 98, the pawl 102 being maintained in position against the abutments by a spring 110 connected to the arm 98 at one end and to an arm of the pawl 102 at its other end. A spring 112 connected at one end to the arm 106 of the treadle lever 24 and at its other end to a stationary arm 114 on the frame 2 maintains the treadle in a raised or inoperative 75 position.

It will thus be seen that the first part of the depression of the treadle 24 causes the shoe holding means or jack 8 to be moved into operative or shoe holding position, due to the connecting rod 28 and the lever 30, and further depression of the treadle effects a single rotation of the eccentric cam 74 to cause the pawl 102 to move the arm 98 out of engagement with the dog 96 and allow it to engage one of the slots 94, thereby connecting the eccentric cam 74 to the continuously rotating hub 92 to raise and lower the sole laying pad once relatively to the shoe held by the jack.

It has been found that in laying unvulcanized rubber soles upon a shoe bottom it is not necessary to subject the sole to a sole laying pressure for any length of time, but, on the contrary, to cause a substantially instantaneous sole laying pressure to be applied to the shoe since the sole is of a character which is readily conformable to the shoe bottom and will adhere to the shoe as soon as brought in contact with the shoe bottom. On the other hand, if the shoe is subjected 100 to a sole laying pressure for any great length of time, the sole is liable to be distorted.

For this reason such a structure as just described is employed. To illustrate this, assume that the driving mechanism is so timed 110 that the shaft 80 is rotating at 30 R. P. M., then the period of time during which sole laying pressure is exerted will be approximately one second. This is ordinarily sufficient and the operator can not accidentally 115 vary it. Hence uniformity in the treatment of all the soles to be laid can be reliably secured because, like machinery in general, whatever is employed to actuate the main shaft 72, will impart a known and constant 120 speed to said shaft.

The illustrated sole laying machine may be used in the manner usually employed in laying soles by machinery, that is, first preliminarily positioning the shoe sole on the 125 lasted shoe bottom by hand and then presenting the assembled shoe to the machine for the sole laying operation. In the contemplated use of the said illustrated machine, however, the lasted shoe and the sole 130

which is to be applied to the shoe are presented to the machine without any preliminary positioning and temporary attachment of the sole to the shoe, this being possible by reason of the novel pressure applying pad of this invention. In accordance with this use of the machine, the unvulcanized sole the upper surface of which is preferably coated with a suitable cement is first placed in the sole shaped mold 44 or shoe sole receiving pocket constituting the pad and then the lasted shoe placed in the mold with the lasted shoe bottom engaging the upper surface of the sole. During this placing of the sole and the lasted shoe on the pad, the jack occupies a laterally displaced position such as indicated by full lines in Fig. 1, the sole-and-shoe-supporting surface of the pad being therefore exposed to enable the operator to watch his work and effect correct assembly of the parts which is important when said parts carry an adhesive. Then, without movement of the shoe and sole from their assembled positions on the pad, the jack swings over to the position indicated by dotted lines in Fig. 1 and the laying pressure begins. The mold thus receives the lasted shoe and the sole in a predetermined relation to the jack, and the walls of the matrix or mold relatively locate the shoe and the sole with respect to each other for the application of sole laying pressure, thus eliminating the initial hand operation heretofore necessary.

In the event that the shoe to be operated on is such as not to be accurately located with respect to the shoe bottom pressing surface and the pressure applying walls of the pad to secure the best results three shoe positioning devices or gages are provided. These devices are preferably located at the end of the shoe, the toe portion and the shank of the shoe respectively, the location of the devices relatively to a shoe corresponding approximately to the points on a shoe which have the least variations over a given range of sizes of shoes. Each of these gages comprises a narrow blade 116 which is adjustably secured by means of a slot and screw connection 117 to the forward end of one arm of a bracket 118 which is pivotally mounted on a pin 119 held in depending lugs formed on the rim 46. A torsion spring 120 is connected to the bracket 118 and the frame so that in the normal inoperative position of the locating devices they are held in retracted position withdrawn from the mold 44 as shown in Fig. 3, a stop arm 121 on the bracket engaging the flange 42 of the container. The gages are projected into operative position in the mold 44 by means of a foot treadle 122. In the operative shoe locating position of the gages, as shown in dotted lines in Fig. 1, the lower ends of the blades 116 are located in the angle between the shoe bottom pressing surface 50 and the side walls 52 of the mold 44 and present substantially vertical walls to engage the shoe and shoe sole. The treadle 122 for projecting the blades 116 into operative position in the mold 44 is fulcrumed on the shaft 26 and connected to its rear end is a rod 124 the upper end of which is received in a guideway formed in the under side of the table 58 of the carrier 56. The rod 124 carries a cross bar 126 upon which are mounted three brackets 128 each containing a spring pressed plunger 130 for engaging a tail piece formed on each of the corresponding brackets 118. Upon depression of the foot treadle 122 the rod 124 carrying the plungers 130 is raised to tip the brackets 118 forwardly and project the blades 116 into vertical position in the mold 44 where they serve as guides for the shoe to locate it properly.

It is contemplated that two molds for laying the soles on right shoes and two molds for laying the soles on left shoes will take care of the range of sizes of shoes to be operated upon. As herein illustrated, the pressure applying pad is adapted to receive the largest shoe of a predetermined range of sizes of shoes and in order to enable the soles of shoes of smaller sizes to be laid by the pad to the best advantage, an auxiliary pressure applying heel pad is provided. This auxiliary pad consists of a heel shaped mat 132 of resilient rubber material of substantially uniform thickness and having an upstanding wall 134 extending around the side and rear edges of the mat, as shown in Fig. 5. Owing to the fact that rubber soles are of substantially greater thickness at the heel than at the shank and forepart of the sole, a flat metal plate 136 is preferably embedded in the mat or heel pad. This plate serves to reinforce the floor of the pad 132 and causes it to exert a substantially perpendicular and flat pressure to the heel end of the sole without distorting the sole. The side walls 134 confine the edge of the heel end of the sole and operate in a manner similar to the side walls 52 of the mold to force the margin of the sole over on to the sides of the shoe as the relative displacement of the liquid in the container causes the mold to be forced into conformation with the bottom and sides of the shoe. For the purpose of positioning the auxiliary pad 132 in the mold according to the size of the shoe to be operated upon and also to assist in maintaining shoes of smaller sizes properly positioned in the mold, the auxiliary pad is provided with two pins 138 which may conveniently be formed on the metal plate 136 and project from the under side of the mat. These pins are received in suitable holes 140 provided in the floor 50 of the mold 44. These holes are formed in two staggered 130

rows, as shown in Fig. 5, which are slightly offset laterally at an angle to the median line of the shoe corresponding to the location in which the heel portions of shoes of a 5 range of sizes will fall when properly positioned in the mold.

In the use of the illustrated machine the operator first places in the mold a sole which is to be laid, and then depresses the treadle 10 122 to cause the gages 116 to be projected into the mold. He then places a lasted shoe upon the sole with the side and one end of the shoe in contact with the gages 116, the purpose of the gages being to facilitate the 15 proper location of the shoe upon the sole. Upon release of the treadle 122, the gages 116 are retracted from the mold by the springs 120. By locating the sole on the shoe through presentation of the shoe to the 20 sole laying machine the necessity of any preliminary location of the sole on the shoe by hand is eliminated. Moreover, the greater accuracy by which this step is performed is of considerable importance since 25 any misplaced or otherwise improperly located sole when rolled over on to the sides of the shoe is very noticeable and detrimental to the neat appearance of the shoe. The operator next depresses the foot treadle 24. 30 The first part of the movement of this treadle causes, through the rod 28 and lever 30, the jack 4 to be moved forward about its pivot 6 into position for the toe post 12 and the heel block 14 to engage their respective 35 portions of the last. Further depression of the treadle causes the arm 106 of the treadle through the latch 102 to move the arm 98 out of engagement with the spring actuated dog 96 on the eccentric and allow it to engage one of the slots 94 in the rotating disk 40 92, whereupon the eccentric is actuated to force the carrier 56 carrying the pressure applying pad upwardly. The shoe in the mold 44 immediately engages toe post 12 and 45 heel member 14 of the jack and is prevented from further upward movement, while the resilient mold 44 yields and allows the carrier and pad to continue its upward movement. This relative movement between the pressure 50 applying pad and the shoe causes the surface 50 of the resilient mold 44 to conform to the contour of the bottom face of the shoe and at the same time the displacement of the water in the container caused by the relative movement acts to exert a substantially uniform 55 sole laying pressure upon the bottom of the shoe. After a substantial part of the movement of approach between the pressure applying pad and the shoe has been effected, 60 sufficient water is displaced to cause the side walls 52 of the mold 44 to be converged or forced into engagement with the sides of the shoe, as illustrated in Fig. 2 of the drawings, to apply a sole laying pressure to the 65 sides of the shoe. This converging move-

ment of the walls 52 occurring simultaneously with a slight vertical movement of the walls causes the marginal portion of the sole to be rolled over onto the sides of the shoe and into intimate contact with the shoe 70 upper. Practically no distortion of the sole can occur during this application of pressure to the sole since the edges of the sole are, at all times, confined by the walls 52 of the mold. Owing to the equalizing character of the medium acting upon the mold 44 to conform it to the exact conformation of the bottom and sides of the shoe, a substantially perpendicular sole laying pressure is applied to all portions of the sole. By reason of the fact that the side walls 52 of the mold are not moved into engagement with the side faces of the shoe until a substantial part of the relative vertical movement between the pad 44 and the shoe is effected a 75 substantially perpendicular pressure is applied to the side face of the shoe without any substantial component of force in the direction of the height of the shoe whereby any friction drag of the side walls upon the shoe 80 is avoided. If the shoe being operated upon is provided with a foxing, as are a great many of the vulcanized shoes, this application of a substantial perpendicular pressure is of extreme importance since otherwise the 85 foxing of the shoe would be injured. Also the side pressure serves to force the foxing into adhesion with the upper whereby a separate hand rolling of the foxing is not necessary. A further advantage gained by causing the application of sole laying pressure to be applied to the bottom of the shoe in advance of the application of pressure upon the sides of the shoe to roll the marginal edge of the sole, is that the possibility of air 90 being trapped between the bottom of the shoe and the sole is reduced to a minimum and consequently a much smaller percentage of "seconds" or defectively vulcanized shoes are produced. Any excess pressure which 95 the shoe might be subject to, due to the varying heights of lasts of different sizes, is taken care of by the spring 28 provided in the jack 8. All of the above described 100 operations are effected quickly, during the 105 upward movement of the pad carrier. During the last half of the single rotation of the eccentric cam 74 the carrier 56 and the pressure applying pad are lowered and the jack returns to its inoperative position indicated 110 by dotted lines in Fig. 1, due to the action of spring 22. No second rotation of the cam can occur unless the treadle 24 is released and again operated because, when the cam 74 and the dog 96 which is pivotally carried 115 thereby, are approaching the end of the revolution, the lug 97 of the dog engages the lower inclined face of the rib 100 so that, during the rest of said revolution, the dog 96 is automatically disengaged from the ro- 120 125 130

tating disk 92. When it is desired to lay the soles of somewhat smaller sizes than the mold was made to accommodate, the auxiliary pad 132 is used. In the use of this pad, 5 it is positioned on the floor of the mold by means of the pins 138 in accordance with size of the shoe to be operated upon and the sole and shoe then placed in the mold in the manner above described, the heel end of the 10 shoe fitting the auxiliary pad so that in the operation of the machine the pad operates upon the shoe in substantially the same manner as the pad 44, the side walls 134 of the 15 pad acting to confine the edges of the heel portion of the sole to prevent distortion of the sole.

Having thus described the invention, what is claimed as new and desired to be secured by Letters Patent of the United States is:—

20 1. A sole laying machine comprising, in combination, means for holding a shoe against pressure applied to the bottom of the shoe, pressure applying means constructed and arranged to be forced into 25 pressing engagement with the bottom of the shoe and with the sides of the shoe adjacent to the bottom, and means for forcing the pressure applying means into pressing engagement with the bottom of the shoe and 30 with the sides of the shoe adjacent to the bottom by a relative movement of translation of the pressure applying means and the means for holding the shoe.

2. A sole laying machine comprising, in 35 combination, means for holding a shoe against pressure applied to the bottom of the shoe, pressure applying means formed and arranged to be forced into pressing relation to the shoe bottom and to the sides of 40 the shoe adjacent to the bottom, and means for effecting movement of the pressure applying means relatively to the shoe holding means to establish said pressure applying 45 means and the shoe.

3. A sole laying machine comprising, in combination, means for holding a shoe and sole pressing means formed and arranged to cause, in response to relative bodily movement between it and the shoe holding means, a sole laying pressure to be applied to the bottom of the shoe and to the side faces of the shoe adjacent to the bottom, and means for causing such relative movement.

55 4. A sole laying machine comprising, in combination, means for holding a shoe against pressure applied to the bottom of the shoe, pressure applying means constructed and arranged to be caused to apply pressure directed substantially perpendicularly to the bottom of the shoe and to the sides of the shoe adjacent to the bottom and means for effecting relative movement of the pressure applying means and the shoe holding

means to establish said pressure applying 65 relation between the pressure applying means and the bottom and the sides of the shoe adjacent to the bottom.

5. A sole laying machine comprising, in combination, means for holding a shoe 70 against pressure applied to the bottom of the shoe, pressure applying means having a shoe bottom pressing surface and another surface constructed and arranged to apply pressure substantially perpendicularly to the 75 sides of the shoe adjacent to the shoe bottom without any substantial component of force in the direction of the height of the shoe, and means for effecting relative movement of the pressure applying means and 80 the shoe holding means to cause pressure to be applied to the bottom of the shoe and to the sides of the shoe adjacent to the bottom.

6. In a sole laying machine, in combination, pressure applying means having a shoe 85 bottom pressing surface and formed and arranged to apply pressure to the sides of a shoe adjacent to the shoe bottom, said pressure applying means being organized to apply pressure perpendicularly to the sides of 90 the shoe without any substantial frictional drag on the shoe upper, means for holding the shoe against pressure applied to the shoe bottom, and means for effecting relative movement of the pressure applying means 95 and the means for holding the shoe to cause pressure to be applied to the bottom of the shoe and to the sides of the shoe adjacent to the bottom.

7. In a sole laying machine, pressure applying means comprising a shoe bottom pressing surface and surfaces normally shaped to apply pressure to the sides of a shoe adjacent to the bottom organized to overlap the marginal edge portion of a sole 105 upon the marginal portions of the sides of the shoe by pressure directed substantially perpendicularly to the sides of the shoe, means for holding the shoe against pressure applied to the shoe bottom, and means for 110 effecting relative movement of the pressure applying means and the means for holding the shoe to establish said pressure applying relation between the pressure applying means and the bottom and sides of the shoe. 115

8. A sole laying machine comprising means for holding a shoe against pressure applied to the bottom of the shoe, pressure applying means and means for effecting relative movement of the shoe holding means 120 and the pressure applying means to cause pressure to be applied to the shoe bottom, said pressure applying means being constructed and arranged to be caused by said relative movement to apply pressure to the 125 sides of the shoe adjacent to the bottom while the bottom of the shoe is being subjected to pressure.

9. In a sole laying machine, pressure applying means having a shoe bottom pressing surface of a shape approximately complementary to the shape of the sole of a shoe and 5 having surfaces formed to apply pressure to the sides of the shoe adjacent to the shoe bottom, means for holding the shoe against pressure applied to the shoe bottom, and means for causing said pressure applying 10 means to apply pressure to the shoe bottom and to the sides of the shoe adjacent to the bottom.

10. A sole laying machine comprising, in combination, means for holding a shoe 15 against pressure applied to the bottom of the shoe, pressure applying means comprising a mold of a normal shape corresponding substantially to the shape of the bottom and to the marginal side faces of a shoe and 20 means organized to force the mold into pressure applying relation to the bottom and to the adjacent side faces of the shoe.

11. A sole laying machine having, in combination, means for holding a shoe against 25 pressure applied to the bottom of the shoe, pressure applying means comprising a mold having a shoe bottom pressing surface normally substantially complementary to the shape of a shoe sole and having walls adapted to be forced into pressing engagement 30 with the sides of the shoe adjacent to the bottom, and means for causing said pressure applying means to apply pressure to the shoe bottom and the sides of the shoe adjacent to the bottom.

12. A sole laying machine having, in combination, means for holding a shoe against pressure applied to the bottom of the shoe, pressure applying means comprising a mold 40 shaped to present a shoe bottom pressing surface normally substantially complementary to the shape of a shoe sole and surfaces formed and arranged to overlap the marginal edge portion of the sole upon the 45 marginal portion of the sides of the shoe by pressure applied substantially perpendicularly to the sides of the shoe, and means for causing said pressure applying means to apply pressure to the shoe bottom and to the 50 sides of the shoe adjacent to the bottom.

13. A sole laying machine comprising, in combination, means for holding a shoe against pressure applied to the bottom of the shoe, pressure applying means, means for 55 effecting relative movement of the shoe holding means and the pressure applying means, and means rendered effective by said relative movement to cause said pressure applying means to apply pressure substantially 60 perpendicular to the bottom of the shoe and to the sides of the shoe adjacent to the shoe bottom.

14. A sole laying machine comprising, in combination, means for holding a shoe

against pressure applied to the bottom of the 65 shoe, pressure applying means, means for effecting relative movement of the shoe holding means and the pressure applying means and means rendered effective upon the first part of said relative movement to cause said 70 pressure applying means to apply pressure to the shoe bottom and upon the latter part of said relative movement to cause the pressure applying means to apply pressure to the sides of the shoe adjacent to the bottom. 75

15. A sole laying machine comprising, in combination, means for holding a shoe against pressure applied to the bottom of the shoe, pressure applying means comprising a mold shaped to present a shoe bottom pressing surface and side walls adapted to apply pressure to the sides of the shoe adjacent to the bottom, means for effecting relative movement of the shoe holding means and the pressure applying means, and means associated with said pressure applying means and rendered effective by said relative movement to cause the walls of the mold to apply pressure to the side faces of the shoe adjacent to the bottom. 80

16. A sole laying machine comprising, in combination, means for holding a shoe against pressure applied to the bottom of the shoe, pressure applying means comprising a mold of a shape which is normally approximately complementary to the bottom and adjacent sides of a shoe and an incompressible medium acting on the mold to cause it to apply pressure to the shoe bottom and to the sides of the shoe adjacent to the bottom. 90

17. A sole laying machine comprising, in combination, means for holding a shoe against pressure applied to the bottom of the shoe, pressure applying means adapted to apply pressure to the bottom of a shoe 10 and having a portion adapted to apply pressure to the sides of the shoe adjacent to the bottom, means for effecting relative movement of said shoe holding means and said pressure applying means to cause pressure 11 to be applied to the shoe bottom, and an incompressible medium adapted to cause the pressure applying means to apply pressure to the sides of the shoe adjacent to the bottom when the relative movement effects the 11: application of pressure to the bottom of the shoe.

18. A sole laying machine comprising, in combination, a shoe support, a sole pressing pad having a conformable mold of a normal shape to present a resilient presser wall adjacent to the bottom and the side faces of a shoe, means for moving said pad toward the shoe support, and a medium arranged to be caused to act upon the mold through the 12: movement of the pad to cause the presser wall to apply pressure to adjacent surfaces of the shoe. 120

19. A sole laying machine comprising, in combination, means for holding a shoe against pressure applied to the bottom of the shoe, pressure applying means comprising a conformable mold of a normal shape corresponding to the general contour of the bottom and the marginal side faces of the shoe, means for effecting relative approaching movement of the shoe holding means and the pressure applying means, and an equalizing medium rendered effective by said relative movement to conform the mold to the exact conformation of the bottom of the shoe and the side faces of the shoe adjacent to the bottom. 65
20. In a sole laying machine, in combination, pressure applying means constructed and arranged to apply pressure to the bottom of a shoe and to the sides of the shoe adjacent to the bottom, a fluid container, a body of fluid interposed between said container and said pressure applying means, and means for holding the shoe against pressure applied to the shoe bottom. 70
21. In a sole laying machine, in combination, pressure applying means constructed and arranged to apply pressure to the bottom of a shoe and to the sides of the shoe adjacent to the bottom, a fluid container, a body of fluid of constant volume interposed between said container and said pressure applying means, and means for holding the shoe against pressure applied to the shoe bottom. 75
22. A sole laying machine comprising pressure applying means having a shoe bottom pressing surface approximately complementary to that of the sole of a shoe and having walls of a normal shape to apply pressure to the sides of the shoe adjacent to the shoe bottom, means for holding the shoe against pressure applied to the shoe bottom, and means for operating said pressure applying means to apply pressure to the bottom of the shoe and to the sides of the shoe adjacent to the bottom, said operating means including a fluid container and a body of fluid of constant volume interposed between said container and said pressure applying means. 80
23. In a sole laying machine, the combination of a sole pressing pad comprising a container having a constant fluid content and a conformable mold having shoe engaging surfaces shaped approximately complementary to the shape of the sole of a shoe and to the sides of the shoe adjacent to the shoe bottom, and mechanism constructed and arranged to depress the shoe a predetermined amount into the pad. 85
24. A sole laying machine, having, in combination, means for holding a shoe against pressure applied to the shoe bottom, a fluid container, a body of fluid in said container, and pressure applying means constructed and arranged to be forced into pressing engagement with the bottom of the shoe upon relative movement of the means for holding the shoe and the pressure applying means, said pressure applying means having surfaces adapted to be forced into pressing engagement with the sides of the shoe adjacent to the bottom through bodily movement of the fluid effected by said relative movement. 90
25. In a sole laying machine, a pressure applying means comprising, in combination, a fluid container, a body of fluid of constant volume in said container, and a conformable mold disposed in the container and shaped to present a shoe bottom pressing surface approximately complementary to that of the sole of a shoe and having walls shaped to apply pressure to the sides of the shoe adjacent to the shoe bottom, said pressure applying means being constructed and arranged to cause the walls of the mold to apply a pressure proportionate to the pressure applied by the bottom pressing surface. 95
26. In a machine for laying the soles of shoes, pressure applying means comprising a fluid container, a body of fluid of constant volume in said container and a conformable mold disposed in said container and having a shoe bottom pressing surface and walls displaceable by fluid pressure into pressure applying relation to the sides of the shoe adjacent to the bottom, said organization being arranged to cause displacement of the walls of the mold to apply pressure to the sides of the shoe after the application of a part of pressure to the bottom of the shoe is established. 100
27. A sole laying machine having, in combination, means for holding a shoe against pressure applied to the shoe bottom, pressure applying means comprising a mold normally shaped to constitute a pocket to receive the bottom of a shoe and the sides of a shoe adjacent to the bottom, and means for causing said mold to apply pressure to the bottom of the shoe and to the sides of the shoe adjacent to the bottom. 105
28. A sole laying machine comprising, in combination, means for holding a shoe against pressure applied to the shoe bottom, a fluid pressure chamber having a conformable shoe engaging member of a normal permanency of shape approximately complementary to the bottom and the side faces of a shoe, and means for causing a fluid pressure to be exerted upon the shoe engaging member to apply sole laying pressure to the shoe. 110
29. A sole laying machine comprising, in combination, means for holding a shoe against pressure applied to the shoe bottom, a fluid pressure chamber having its shoe en- 115
- 120
- 125

- gaging surface shaped normally to maintain a shoe sole and the shoe in position for proper presentation with respect to the shoe holding means, and means for causing a fluid pressure to be exerted upon the shoe engaging member to apply sole laying pressure to the shoe. 5
30. In a sole laying machine, in combination, means for holding a shoe against pressure applied to the bottom of the means in the form of a resilient diaphragm formed normally to provide a pocket for a shoe sole, and means for locating a lasted shoe in predetermined relation to the sole in the sole receiving pocket of the pad. 10
31. In a sole laying machine, in combination, means for holding a shoe against pressure applied to the bottom of the shoe, a pressure applying pad in the form of a resilient diaphragm formed to provide a sole receiving pocket, manually controlled means for positioning a lasted shoe on the pad relatively to a sole located in the pocket, and means for effecting an operation of said pressure applying pad. 15
32. A sole laying machine having, in combination, pressure applying means having a shoe bottom pressing surface and surfaces shaped to apply pressure to the sides of a shoe adjacent to the shoe bottom and to effect a relative positioning of a shoe and a shoe sole to locate the sole with relation to the bottom of the shoe, means for holding the shoe against said sole laying pressure, and means for effecting relative movement of the pressure applying means and the means for holding the shoe to apply pressure to the bottom of the shoe and to the sides of the shoe adjacent to the bottom. 20
33. A sole laying machine having, in combination, pressure applying means comprising a mold adapted to receive a lasted shoe and a shoe sole, means associated with said mold for effecting a relative positioning of the shoe and the shoe sole to locate the sole with relation to the bottom of the shoe, means for holding the shoe against sole laying pressure, and means for effecting relative movement of the pressure applying means and the means for holding the shoe to apply sole laying pressure to the shoe. 25
34. A sole laying machine having, in combination, pressure applying means comprising a mold for receiving a lasted shoe and a shoe sole, means adapted to be projected into said mold to effect a relative positioning of the shoe and the sole preliminarily to the application of sole laying pressure, means for holding the shoe against sole laying pressure, and means for effecting a relative movement of the pressure applying means and the means for holding the shoe to apply sole laying pressure to the shoe. 30
35. A sole laying machine having, in combination, pressure applying means comprising a mold receiving a lasted shoe and a shoe sole, a plurality of gaging devices movable to effect a relative positioning of the shoe and the shoe sole, means for moving said devices into positioning relation to the shoe and the shoe sole, means for holding the shoe against sole laying pressure, and means for effecting a relative movement of the pressure applying means and the means for holding the shoe to apply sole laying pressure to the shoe. 35
36. A sole laying machine having, in combination, a pressure applying means comprising a mold for receiving a lasted shoe and a shoe sole, a plurality of gaging devices movable to effect a relative positioning of the shoe and the shoe sole in the mold, manually operated means for simultaneously moving said devices into positioning relation to the shoe and the shoe sole, means for holding the shoe against sole laying pressure, and means for effecting a relative movement of the pressure applying means and the means for holding the shoe to apply sole laying pressure to the shoe. 40
37. A sole laying machine having, in combination, pressure applying means comprising a mold for receiving a lasted shoe and a shoe sole, means for effecting a relative positioning of the shoe and the shoe sole to locate the shoe sole with relation to the shoe bottom comprising a plurality of feelers adapted to be projected into the mold, manually controlled means for operating said feelers, means for holding the shoe against sole laying pressure, and means for effecting a relative movement of the pressure applying means and the means for holding the shoe to apply sole laying pressure to the shoe. 45
38. A sole laying machine having, in combination, means for holding a shoe against sole laying pressure, a pressure applying pad formed and arranged to effect a relative positioning of the shoe and the shoe sole to locate the sole with relation to the bottom of the shoe, means for positioning the shoe and the shoe sole relatively to the shoe holding means, and means for effecting relative movement of the pressure applying means and the means for holding the shoe to apply sole laying pressure to the shoe. 50
39. A sole laying machine having, in combination, means for holding a shoe against sole laying pressure, pressure applying means, a plurality of shoe and shoe sole positioning devices, means for moving said devices into operative relation to the pressure applying means, said pressure applying means having vertical walls to assist in locating the shoe and the shoe sole in definite relation to each other and to the pressure applying means, and means for effecting rel- 55

ative movement of the pressure applying means and the means for holding the shoe to apply pressure to the bottom of the shoe and to the sides of the shoe adjacent to the bottom.

40. In a sole laying machine, a pressure applying device for a sole laying machine comprising a flexible mold having a bottom shaped substantially complementary to that of the bottom of a shoe and having side walls adapted to apply pressure to the sides of a shoe adjacent to the bottom, and a member located in the heel portion of the mold having a relatively firm shoe bottom engaging portion and upstanding walls to engage the sides of the shoe, said mold and member being provided with a plurality of interengaging connections to permit the member to be adjusted into different positions in the mold.

41. A machine of the class described, having, in combination, a flexible elastic member adapted to support a shoe, a jack laterally movable into and out of register with the elastic member, means for normally holding the jack in laterally displaced position out of register with the elastic member, and operator-controlled means for shifting the jack from displaced position to a position in register with the elastic member and for effecting movement of approach between the jack and member while they are in register with each other.

42. A machine for laying unvulcanized rubber soles, having in combination, a flexible diaphragm, means for causing the diaphragm to press the sole against the bottom of a shoe and to bend it up about the lower side walls of the shoe and a jack for supporting the shoe, said jack being pivoted in such manner that it may be swung into and out of register with the diaphragm, a spring normally holding the jack out of register, and treadle controlled means for moving it into register at the will of the operator.

43. A machine of the class described having, in combination, a flexible pad including a flexible diaphragm having a surface for supporting an assembled sole and lasted shoe thereon, a shoe-holding jack laterally movable to and from position above the pad, means for normally retaining the jack in laterally displaced position, and operator-controlled means for shifting the jack from displaced position to a position above the diaphragm and for effecting relative movement of approach between the jack and diaphragm while the jack is above the diaphragm.

44. A sole laying machine having, in combination, a flexible pad including a flexible diaphragm having a surface for supporting

an assembled sole and lasted shoe thereon, a shoe-holding jack laterally movable to and from position above the pad, means for normally retaining the jack in laterally displaced position, and treadle controlled means for shifting the jack from displaced position to a position above the diaphragm and for thereafter effecting relative movement of approach between the diaphragm and jack.

45. A machine for pressing an unvulcanized sole against the bottom and lower side walls of a shoe, having in combination, an elastic diaphragm on which the sole of the shoe may be placed, a jack for supporting the shoe, guiding means adapted to contact with the sides of the shoe and with respect to which the shoe is movable in a direction toward the diaphragm for facilitating the proper locating of the shoe, and means for effecting relative movement of approach of the jack and diaphragm and for causing the diaphragm to press the sole against the bottom of the shoe and to bend the edge of the sole up around the lower side walls of the shoe.

46. A sole laying machine comprising, in combination, an upwardly facing elastic member adapted to permit assembling thereon of a sole and a lasted shoe, gaging means arranged to contact with the sides of the shoe to facilitate proper assembling of the shoe on the sole, a jack for supporting the shoe, and means for causing the elastic member to press against the bottom of the shoe and to rise around the sides thereof.

47. A sole laying machine comprising, in combination, an upwardly facing elastic member adapted to permit assembling thereon of a sole and a lasted shoe, gaging means arranged to contact with the sides of the shoe to facilitate proper assembling of the shoe on the sole, a jack for supporting the shoe, and means including a substantially incompressible fluid medium for causing the elastic member to press against the bottom of the shoe and to rise around the sides thereof.

48. A sole laying machine comprising an elastic diaphragm for contacting with the sole of a shoe, means for facilitating the locating of a sole thereon in a predetermined position, means with respect to which the shoe is movable for facilitating the location of a lasted shoe in proper position on the sole, means for supporting the shoe, and means for causing the diaphragm to press against the bottom and lower side walls of the shoe.

In testimony whereof I have signed my name to this specification.

LOUIS A. CASGRAIN.
